CLAIM

The ornamental design for a cowl, as shown and described.

DESCRIPTION

FIG. 1 is a front, right side perspective view of a cowl showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

A second embodiment of the claimed design for the cowl is a mirror image of the cowl as shown in FIGS. 1 to 7.
